CARBURETOR FLOAT SUPPORT

Filed April 30, 1938

UNITED STATES PATENT OFFICE

2,202,993

CARBURETOR FLOAT SUPPORT

Byron Mollberg, St. Louis, Mo., assignor to Carter Carburetor Corporation, St. Louis, Mo., a corporation of Delaware

Application April 30, 1938, Serial No. 205,373

6 Claims. (Cl. 137—104)

This invention relates to pivotal support means for valve controlling floats of the type commonly used to control the fuel inlet valve in an internal combustion engine carburetor.

5 An object of the invention is to provide substantially simplified pivotal supporting means for valve control means of the above type.

Another object is to provide pivotal support for a float of the above type arranged so that the 10 float may be readily assembled and disassembled upon removal of the float chamber cover without the necessity of disturbing or removing any other part of the mechanism.

These objects and other more detailed objects 15 hereafter appearing are attained substantially by the devices illustrated in the accompanying drawing in which:

Fig. 1 is a sectional view illustrating part of an internal combustion engine carburetor embodying the invention.

Fig. 2 is a top view of a part of the structure in Fig. 1.

Fig. 3 is a section taken substantially on the corresponding section line of Fig. 1.

25 Fig. 4 is a vertical section showing a part of the structure in Fig. 1, but with the float bowl cover removed.

Fig. 5 is a perspective view showing the float supporting portion of the float chamber wall, and

30 Fig. 6 is a similar view showing the float.

Fig. 1 shows a downdraft carburetor including air inlet horn 1 mounting choke valve 2, mixing chamber 3, and outlet portion 4 flanged as at 5 for attachment to the intake manifold (not

35 shown) of an associated internal combustion engine. A throttle valve 6 is pivotally mounted between the mixing chamber and outlet portion of the carburetor. Adjacent the mixture chamber is a float bowl 7 having an apertured inlet boss

40 8 receiving a valve seat member 9 and a needle valve 10. Valve 10 is controlled by a tongue 11

on float 12, the tongue forming part of the float supporting bracket, generally indicated at 13.

Fuel is supplied to the mixture chamber through 45 a calibrated orifice member 14, and passage 15, extending upwardly at an angle through jet bar 16 and opening laterally therethrough by means of ports as at 17. The main fuel passages are

50 air bled by means of a passage 18 opening into the top of the float chamber, and perforated tube 19.

The outer wall of float chamber 7 is recessed adjacent boss 8, as at 20, to form a ledge 21 beneath valve seat member 9. Projecting from ledge 55 21 are lugs 22, 23 and 24. Float bracket 13 in-

cludes side arm portions 25, having recesses 26 in the outside edges thereof.

In assembling the float with the carburetor, bracket 13 is inserted into recess 20 from the top or inner side and recesses 26 are applied over lugs 5 22 from the top thereof. In the assembled position, the bracket arms rest upon lugs 23 which have curved or tapered upper surfaces forming pivotal supports. Lugs 22 and 23 prevent disassembly of the float except by upward movement 10 thereof.

Cover portion 27 of the float bowl includes an inverted U-shaped projection 28 depending therefrom on each side of valve seat member 9, as shown in Fig. 3, and with its lower extremities 15 normally positioned immediately above bracket 13 so as to prevent upward movement thereof. Thus lugs 22 and 23 and element 28 form a stable pivotal support for the float which may be readily assembled and disassembled when the cover is 20 removed without the necessity of first removing a float supporting pin or other holding means, as has frequently been the case.

As shown in Fig. 4, needle valve 10 normally extends slightly inwardly beyond the inner extremity of seat member 9 and in order to remove the valve seat element, which is pressed into place, a screw driver may be inserted behind lug 24, as indicated, and pressure applied to the exposed end of the valve. This inlet valve construction is more fully described and claimed in my co-pending application, Serial No. 205,372, filed April 30, 1938, of which this application is a continuation-in-part.

The invention is not limited to the structure 35 shown but may be modified in various respects as will occur to those skilled in the art and the exclusive use of all such modifications as come within the scope of the appended claims is contemplated.

40 I claim:

1. In combination, a float chamber, a port in a wall thereof, a valve in said port, a float arranged for controlling said valve and having a supporting bracket including a recessed part, lug structure on the wall of said chamber engaging the under side of said bracket and pivotally supporting the same, and other lug structure on said wall extending into said recessed part of said bracket for resisting disassembly of said bracket from said supporting lug structure.

2. The combination of elements specified in claim 1 further including a removable cover for said chamber having a member normally posi-

- tioned adjacent said bracket for preventing dis-
assembly thereof from said lug structure.
3. The combination of elements specified in
claim 1 in which the recessed part of said float
5 bracket extends along the inner and side portions
of said second mentioned lug structure whereby
disassembly of said bracket from said lug structure
is prevented except by vertical movement of
said bracket.
- 10 4. In combination, a float chamber, a port in
a wall of said chamber, a valve in said port, a
float in said chamber arranged for controlling said
valve, a valve engaging bracket on said float having
15 recesses in the side edges thereof, lug structure
on the wall of said chamber engaging the

underside of said bracket for pivotally supporting
the same and spaced lugs on said wall extending
into said recesses whereby assembly and disas-
sembly of said float with said chamber can be ef-
fected only by upward movement of said bracket 5
relative to said lugs.

5. The combination of elements specified in
claim 4 further including a cover for said chamber
having a member normally disposed above said
bracket for securing the same in position. 10

6. The combination of elements specified in
claim 4 in which said bracket includes a lip por-
tion for cooperating with said valve.

BYRON MOLMBERG. 15
